United States Patent Office.

JOHN PRICE, OF NEW YORK, N. Y.

Letters Patent No. 65,941, dated June 18, 1867.

IMPROVED FORGING APPARATUS.

The Schedule referred to in these Letters Patent and making part of the same.

TO ALL WHOM IT MAY CONCERN:

Be it known that I, JOHN PRICE, of the city, county, and State of New York, have invented certain new and useful Improvements in Power-Hammers; and I do hereby declare that the following is a full, clear, and exact description thereof, reference being had to the accompanying drawings, and to the letters of reference marked thereon.

The object of my invention is to provide a means for catching and holding the hammer at or near its highest elevation whenever the operator desires more time to manipulate the work than that which can be used between two strokes of the hammer, whenever the power which drives the hammer is disconnected, or in any other case where it is desired to stop the hammer at or near its highest point. It consists of a rack, spring, and sliding-catch so constructed and arranged in relation to the hammer-head that on sliding the said catch toward the said rack it will take into the teeth of the latter and stop the hammer, the said spring receiving the shock and preventing the breaking of the parts. It consists, also, in a combination of certain devices hereinafter described for imparting motion to the said sliding-catch to stop the hammer, as set forth, when the power which drives the said hammer is disconnected. In the accompanying drawings—

Figure 1 is a front elevation, with my improvements attached thereto, of one of that class of hammers in which the hammer-head itself is driven by means of a piston, working in a cylinder, which is, in turn, driven by a crank and connection from the driving-shaft.

Figure 2 is a side elevation of the same.

Figure 3 is a detail view of the devices for disconnecting the power.

Figure 4 is a vertical section parallel to the front of fig. 1, and passing through the rack, spring, and sliding-bolt.

Figure 5 is a top view of the hammer-head.

Figure 6 is a section of the same through the line $z z$, fig. 4.

A is the hammer, B the piston, C the cylinder, and E the frame of the machine. A projection or yoke, F, is cast on the hammer-head and a recess made immediately under the middle of the said yoke in the said hammer-head. In this recess and under this yoke are placed the rack G and spring or springs H H. A rod, I, passes through the said springs through the top of the yoke F and screws into the head of the rack G, the object of having the rod I so connected being to furnish a means for inserting or removing the said rack and spring, and to do this the rod I is unscrewed and removed. A square head on the rod enables me so to remove it. In a recess or slot in one of the jaws or ways on which the hammer slides is placed the sliding-bolt or catch J, which takes into the teeth on the rack G to stop the descent of the hammer, when operated for that purpose by any suitable device. The devices which are used for operating this sliding-catch J in the form shown in the drawings are seen in figs. 1, 2, and 3. A crank, a, on the rock-shaft f, is connected to the sliding-catch J by the pin C, which works in the slot d in the crank a. The rock-shaft b is driven by a crank, e, and connection, f, from the levers g, on which the friction-pulley h is hung in such a way that when the said friction-pulley is pressed up against the belt i, by bearing down on the handle j the same motion withdraws the sliding-catch J from the rack G and allows the hammer to operate, and when the pressure is taken from the handle j and the friction-pulley h falls back from the belt i, the said sliding-catch J is thrown in so as to take into the teeth on the rack G and stop the hammer. These devices form a convenient and cheap means for operating the sliding-catch J when my improvements are attached to a power-hammer of the form and construction shown, but it is very obvious that the principal feature of my invention, i. e., the combination with a hammer-head of a rack, spring, and sliding-catch, is equally applicable to almost or quite any form of power-hammer in which the hammer itself has a reciprocating motion. Much difficulty has been experienced in the operation of power-hammers for the following reasons: that they cannot in many cases be stopped quickly enough; that the operator cannot stop them while the hammer is up in order to turn or otherwise manipulate the work in hand; and that the hammer-head rests on the lower die when the hammer is stopped, rendering it necessary to start the hammer and put the work on "between two blows," which is often a very difficult operation. All these difficulties are overcome by my invention.

It is obvious that various modifications of this invention may be employed without departing in any essential particular therefrom, as, for example, the rack and spring may be inserted in a proper recess in one of the side pieces or ways, and the sliding-catch set in a channel or opening in the hammer-head and operated by a slide or other device which might be brought to bear on the end of the said catch or on a pin projecting from it. I do not, consequently, confine myself to the exact construction shown, but I claim—

1. The combination, with the hammer-head, of a rack, spring, and sliding-catch, substantially as and for the purpose set forth.

2. Operating the sliding-catch J by means of the lever g, which connects and disconnects the power for driving the hammer, the said lever g being connected for that purpose to the sliding-catch J by the arm a, rock-shaft b, arm e, and connecting-rod or link f, or by their equivalents, in such a manner that the said sliding-catch J will be thrown inward to catch the hammer when the power is disconnected, and drawn out to release the hammer when the power is applied by the lever g, substantially as and for the purpose set forth.

JOHN PRICE.
